CLIP FOR A WRITING INSTRUMENT OR SIMILAR ARTICLE

Bertram A. Strauss, 177—33 Edgerton Road,
Jamaica 32, N.Y.

Filed Nov. 2, 1961, Ser. No. 67,349

Term of patent 14 years

(Cl. D47—17)

Fig. 1

Fig. 2

Fig. 4

FIG. 1 is an isometric view of a clip for a writing instrument or similar article showing my new design. The writing instrument to which the clip is attached is shown in dotted lines for illustrative purposes only.

FIG. 2 is a front elevational view thereof.

FIG. 3 is a side elevational view thereof.

FIG. 4 is a bottom plan view thereof.

I claim:

The ornamental design for a clip for a writing instrument or similar article, as shown and described.
